DESIGN FOR A HANDKERCHIEF

Morris S. Levy, Brooklyn, N. Y.

Application March 11, 1944, Serial No. 112,865

Term of patent 3½ years

(Cl. D3—12)

To all whom it may concern:

Be it known that Morris S. Levy, a citizen of the United States of America, residing at Brooklyn, in the county of Kings and State of New York, has invented a new, original, and ornamental Design for a Handkerchief, of which the following is a specification, reference being had to the accompanying drawing, forming part thereof.

I claim:

The ornamental design for a handkerchief, as shown.

MORRIS S. LEVY.
